(57) **CLAIM**

The ornamental design for a printed beverage container, as shown and described.

DESCRIPTION

FIG. 1 is a top perspective view of our new design for a printed beverage container.

FIG. 2 is another top perspective view thereof.

FIG. 3 is a side elevation view thereof.

FIG. 4 is a top plan view thereof.

FIG. 5 is a bottom plan view thereof.

FIG. 6 is a cross-sectional view thereof, taken along line 6-6 of FIG. 4; and,

FIG. 7 is another cross-sectional view thereof, taken along line 7-7 of FIG. 4.

The broken line arrows in FIG. 4 depict cross-sectional indicia and form no part of the claimed design.

1 Claim, 7 Drawing Sheets
